UNITED STATES PATENT OFFICE.

ANDREW ROBESON, OF NEWPORT, RHODE ISLAND.

DESIGN FOR A METAL HOOK.

43,061.

Specification for Design.

Patented Sept. 24, 1912.

Application filed June 8, 1912. Serial No. 702,565. Term of patent 14 years.

To all whom it may concern:

Be it known that I, ANDREW ROBESON, a citizen of the United States, residing at Newport, in the county of Newport and State of Rhode Island, have invented a new, original, and ornamental Design for a Metal Hook, of which the following is a specification, reference being had to the accompanying drawing, forming part thereof.

Figure 1 is a plan view of a metal hook, showing my new design, a straight piece of metal with one edge serrated and bent and

the other enlarged in the design as shown with two triangular open spaces. Fig. 2 is a side view of a metal hook, showing my new design with serrated edge bent.

I claim:

The ornamental design for a metal hook, as shown and described.

ANDREW ROBESON.
